US00D776710S

(12) United States Design Patent (10) Patent No.: US D776,710 S
(45) Date of Patent: * Jan. 17, 2017

(54) DISPLAY SCREEN OR PORTION THEREOF WITH GRAPHICAL USER INTERFACE

(71) Applicant: Samsung Electronics Co., Ltd., Suwon-si (KR)

(72) Inventors: Su-Hyun Na, Seoul (KR); Na-Ri Kim, Seoul (KR); Olivia Lee, Seoul (KR)

(73) Assignee: SAMSUNG ELECTRONICS CO., LTD., Gyeonggi-Do (KR)

() Term: 14 Years

(21) Appl. No.: 29/504,584

(22) Filed: Oct. 7, 2014

(30) Foreign Application Priority Data

Apr. 8, 2014 (KR) 30-2014-0017529

(51) LOC (10) Cl. 14-04

(52) U.S. Cl.

USPC D14/489

(58) Field of Classification Search

(57) CLAIM

We claim, the ornamental design for a display screen or portion thereof with graphical user interface, as shown and described.

DESCRIPTION

The FIGURE is a front view of a display screen or portion thereof with graphical user interface, showing our new design.

The broken lines illustrating portions of the display screen or portion thereof with graphical user interface form no part of the claimed design.

1 Claim, 1 Drawing Sheet
